UNITED STATES PATENT OFFICE.

CLEMENT C. CLAWSON, OF FLAGTOWN, NEW JERSEY.

COIN-CONTROLLED VENDING-MACHINE.

969,844.

Specification of Letters Patent. Patented Sept. 13, 1910.

Application filed August 4, 1908. Serial No. 446,859.

To all whom it may concern:

Be it known that I, CLEMENT C. CLAWSON, a citizen of the United States, and a resident of Flagtown, in the county of Somerset and State of New Jersey, have invented 5 certain new and useful Improvements in Coin-Controlled Vending-Machines, of which the following is a specification.

The invention relates to improvements in 10 coin-controlled vending machines, and it consists in the novel features and structure hereinafter described, and particularly pointed out in the claims.

While my invention is capable of embodiment in machines adapted for the sale of various articles, I present the same herein, for illustration, in a machine intended for the sale of flat rectangular packages containing a towel and a piece of soap wrapped 15 therein, and said machine comprises a cabinet to contain a stack of the packages, a stationary plate at the bottom of the cabinet containing an opening whose edges are on the same vertical planes as the inner walls 20 of the cabinet, a rotary goods-ejector plate directly below said stationary plate and having an opening corresponding with the opening therein, a base-plate directly below said goods-ejector plate and having an opening 25 corresponding with the opening in said stationary plate but at opposite portions always out of register therewith, and suitable receptacles below said base-plate to receive the coins and temporarily support the packages discharged from the stack by the goods 30 ejector. When the ejector-plate is in its initial position the stack of packages, at its corners, rests on the base-plate with the bottom package within the opening in the 35 ejector-plate, said opening then being in register with the opening at the bottom of the cabinet and out of register with the opening in said base-plate, and when the ejector-plate is moved to its operated position its 40 opening and the package therein are turned into register with the opening in said base-plate and out of register with the opening at the bottom of the cabinet, whereby the package in the ejector-plate becomes unsupported and falls through the opening in the 45 base-plate and the stack is left supported, at its corners, on said ejector-plate. When the ejector-plate is returned to its initial position, its opening passes into register with 50 the opening at the bottom of the cabinet and the stack settles down on the base-plate, the

bottom package entering the opening in the ejector disk or plate and resting at its corner portions on said base-plate.

The invention will be fully understood 60 from the detailed description hereinafter presented, reference being had to the accompanying drawings, in which:

Figure 1 is a perspective view, partly broken away, of a vending machine, constructed in accordance with and embodying my invention; Fig. 2 is a detached perspective view of one of the packages sold by the machine; Fig. 3 is a horizontal section, partly broken away, through the cabinet of 70 the machine, about on the dotted line 3—3 of Fig. 1, the ejector plate being indicated in its initial position preparatory to the machine being operated; Fig. 4 is a substantially corresponding section of the same 75 illustrating the ejector plate in its operated position, the aperture in said plate then being in vertical line with the aperture in the base plate on which it rests; Fig. 5 is a vertical section through a portion of 80 the machine on the dotted line 5—5 of Fig. 3, the ejector plate being indicated in its initial position by solid lines and in its operated position by dotted lines; Fig. 6 is a detached perspective view of the lower 85 portion of the cabinet and plate secured to the bottom thereof and forming a chamber to receive the rotary goods ejector plate; Fig. 7 is a detached perspective view of the goods ejector plate; Fig. 8 is a detached 90 perspective view of the base plate to which a coin receptacle and a receptacle for the goods sold are secured and upon which the bottom plate shown in Fig. 6 is secured with the goods ejector plate shown in Fig. 7 95 resting within the circular chamber represented in Fig. 6; Fig. 9 is a detached sectional view through a portion of the assembled plates represented in Figs. 6, 7 and 8, and is presented to illustrate the operation 100 of the spring dog which prevents the rotation of the goods ejector plate at improper times, Fig. 9 showing a coin in the coin hole of the ejector plate with the spring dog riding over it in regular operation of 105 the machine; and Fig. 10 is a like view of the same illustrating the operation of the dog in preventing the rotation of the ejector plate when a coin is absent from the coin receiving hole in said plate.

In the drawings, 15 designates the cabinet of the machine, 16 a removable front

door for the same, 17 a stack of packages held within said cabinet and to be sold, and 18 a suitable weight placed upon the upper end of the stack 17 for assuring the downward feed of the packages.

Upon the lower end of the cabinet 15 is secured a frame comprising a plate 19 having an upwardly extending flange 20 to receive the lower edges of the cabinet 15 and 10 a downwardly extending flange 21 which rests upon a base-plate 22 and forms, with an auxiliary flange 23 (Fig. 6), a cylindrical chamber for the rotary goods-ejector plate 25. The plate 19 has formed in it 15 within the outline of the flange 20 an opening 26 which is in vertical line with the inner surfaces of the cabinet 15 and of an outline corresponding with the packages 17 to be sold by the machine. At one portion 20 the flange 21 curves inwardly to form the receiving space 27 for the coins to be fed in the machine, and said flange 21 at the space 27 and along a line extending to one side thereof is cut away, as at 28, to form a 25 runway for the handle 29 of the goods ejector plate 25.

Adjacent to the runway 28 and pivotally secured to the underside of the plate 19, within the outline of the flange 21, is a dog 30 which is acted upon by a spring 31. The operating end of the dog 30 constantly presses downwardly against the goods-ejector plate 25, and when a coin 32 is in the receiving hole 33 of said plate, the dog 30 will 35 permit the plate 25 and coin 32 to ride along under it in the manner denoted in Fig. 9. Should, however, an attempt be made to operate the plate 25 without the coin being in the hole 33, the dog 30 would have its 40 operative end projected into said hole 33 and check the movement of the plate 25, in the manner indicated in Fig. 10. The dog 30 prevents the operation of the plate 25 when the hole 33 is empty, or when a coin deficient 45 in thickness is placed in said hole, or when a coin or piece of metal of greater than the predetermined thickness is placed in said hole, and also when a washer is placed in the hole 33. If a coin or piece of metal of 50 greater than the predetermined thickness is placed in the hole 33, the dog 30 will engage its edge and stop the movement of the plate 25, and should a washer be placed in the hole 33, the downwardly projecting end of the 55 dog would enter the hole in the washer and operate to prevent any further movement of the plate 25.

The goods-ejector plate 25 is a plain flat plate having an opening 34 therein corresponding with the opening 26 in the plate 19 and encompassed by an upwardly extending edge-flange 35 which gives to the plate 25 around the opening 34 a depth or thickness equal to the thickness of the individual packages 17, which, one after another, enter

the opening 34 and are by the rotation of the plate 25, moved to a position at which they may descend or fall through said opening. The hole 33 in the plate 25 is of a dimension to snugly receive a five cent piece 70 or such other coin as may be determined upon, and the plate 25 about the hole 33 should be of the same thickness as the coin to be placed in said hole so that when the coin is in the hole, the upper surface of the 75 coin may be on a level with the upper surface of the plate. The plate 25 is formed with an operating handle 29 and also with a segmental slot 36 which permits of the passage of a screw from the hole 37 (Fig. 6) in the plate 19 to the hole 38 (Fig. 8) in the base plate 22 without interfering with the rotation of the plate 25. The plate 25 is received snugly within the lower edges of the 80 circular flanges 21, 23, and is concealed within the chamber formed by said flanges except at the handle 29 which always projects outwardly and with the exception of that portion of the plate which may be exposed at the opening 27 for admitting the coin to the 85 hole 33 in said plate 25.

The base-plate 22 affords a support for the goods-ejector plate 25, and closes the lower end of the chamber formed by the flanges 21, 23. At their rear edges the plates 19, 22 95 abut against the wall to which the cabinet 15, in an angular relation, may be secured by suitable brackets, not shown. The base-plate 22 has formed in it a hole 39 of rectangular outline corresponding in size and shape with the hole 34 in the plate 25 and the hole 26 in the plate 19. The plate 22 is also formed with a hole 40 which is slightly less in diameter than the coin receiving hole 33 in the plate 25 and is directly 100 below said hole 33 when the latter is in the position to receive a coin, the latter resting at its edges on the plate 22 over the hole 40 and within the hole 33. If a small coin or 105 piece of metal should be placed in the hole 33, it would not be supported around the edges of the hole 40 but would fall through said hole. The plate 22 is also formed with an opening 41, the latter being in a position 110 to permit a coin in the hole 33 to fall through it when the goods-ejector plate 25 has been moved to its operated position. Below the plate 22 is secured a receptacle 42 having a front opening 43. Each package discharged by the ejector plate 25 falls into the receptacle 42 and may be removed 115 through the opening 43 thereof. Upon the side of the receptacle 42 is provided a coin receiver or receptacle 44, the latter being hinged at its lower inner edges to the side of the receptacle 42 and provided with a lock 120 45 for securing it in its closed position.

In the employment of the invention the packages 17 will be stacked within the cabinet 15, and the goods-ejector plate 25 being 125

- in its initial position shown in Figs. 1 and 3, the lower package of the stack will be within the hole 34 of said plate 25, as shown in Fig. 5, but will be prevented from falling 5 through said hole 34 because of the fact that it is resting at its four corners on the base plate 22. When the ejector plate 25 is in its initial position the hole 34 therein has its side and end edges on the same vertical 10 plane with the hole 26 in the plate 19, and at this time the entire stack of packages finds its bearing upon the plate 22 whose hole 39 is not on the same vertical plane with the hole 34 in the plate 25 and hole 26 15 in the plate 19, but lies angularly across the plane of said holes 34, 26, thereby exposing portions of the plate 22 to what may be said to be the corners of the stack of packages. The hole 39 in the plate 22 is always 20 in cross-angular relation to the hole 26 in the plate 19 indicated in Fig. 3, and when the plate 25 is in its initial position, its hole is directly on the same vertical plane with said hole 26. After a nickel has been placed 25 in the hole 33 of the plate 25 the latter may be rotated within the flanges 21, 33, the handle 29 moving along the recess 28 until the hole 34 in said plate moves into an angular relation to the hole 26 in the plate 19 30 and into exact parallelism with the hole 39 in the plate 22. This movement of the plate 25 results in the bottom package 17 inclosed within its hole 34 moving with the plate and passing into exact vertical alignment with the hole 39 in the plate 22, the result being that when the plate 25 reaches its operated position, the package which was confined in the hole 34 is left unsupported 35 and falls through the hole 39 and into the receptacle 42, whence it may be taken by hand through the front opening 43. At each end of the recess 28 is formed a shoulder against which the handle 29 will strike for arresting the plate 25 in its initial position 40 and in its operated position. The only moving parts the machine possesses are the goods ejector plate 25 and dog 30, and with each movement of the plate 25 from its initial position shown in Figs. 1, 3 and 5, to its 45 operated position shown in Fig. 4, one package 17 will be left unsupported and fall into the receptacle 42. During the movement of the ejector plate 25 from its initial position to its operated position, said plate, while 50 moving the bottom package to a position to fall through the hole 39 in the plate 22, supports all of the remaining packages in the stack, said plate angularly turning the lower package into vertical line with the hole 39 55 and at the same time causing the sides and ends of its hole 34 to cross the corners of the hole 26 in the plate 19, said edges, represented by the flanges 35, taking the position indicated by dotted lines in Fig. 5 and supporting the entire stack of packages above 60 them. Upon the return of the ejector plate 25 to its initial position, the edges of the hole 34 will pass into exact vertical line with the edges of the hole 26 in the plate 19, and upon attaining such position the entire 70 stack of packages will settle down and become supported on the plate 22, as before, the bottom package of the stack passing into the hole 34 of said plate 25 preparatory to being carried to its discharging position 75 upon the next operation of said plate 25. When the plate 25 is in its initial position the stack of packages is therefore supported directly on the plate 22, and when the plate 25 is moving toward and is at its operated 80 position, the stack of packages, less the bottom package, rests, at its corners, on said plate 25.
- I have hereinbefore sufficiently described the operation of the dog 30. 85
- The plate 19 covers the movable goods-ejector-plate 25 and in the construction shown extends below the edges of the cabinet 15, but it is not essential, though preferable, to extend the plate 19 below the edges 90 of the cabinet since the cabinet is open at its lower end and corresponds at said opening with the polygonal openings in the goods-ejector-plate 25 and base-plate 22. 95
- The chamber within the cabinet corresponds in cross-sectional outline with the shape of the rectangular packages 17, which are all of uniform rectangular edge outline and uniformly stacked one upon the other, the side walls of said chamber serving to 100 confine the stack of packages and guide the same as it gradually lowers through said chamber. The packages 17 are square in edge outline, and the openings 26, 34 and 39, respectively, in the bottom of the cabinet, 105 plate 25 and plate 22 are of uniform size and square in edge outline.
- One of the advantages of my invention is that the openings 26, 34 and 39 are always directly below one another, although not 110 having their edges on the same vertical planes with one another, and the result of this is that the chamber in the cabinet may have smooth plain walls, that the apparatus is strong and compact, that it may dispense 115 packages which are square in edge outline and that the packages may be uniformly stacked one upon another, as distinguished from being "cross stacked" as expressed and shown in the prior art. 120
- I have shown and described the details of the most satisfactory embodiment of the invention known to me, without intending to confine my claims to such embodiment further than the claims themselves indicate. 125
- What I claim as my invention and desire to secure by Letters-Patent, is:
1. In a vending machine, a cabinet containing a vertical chamber which is rectangular in cross-section and adapted to snugly 130

receive a stack of uniformly piled rectangular packages to be sold, the bottom of said chamber being entirely open, as at 26, for the descent of said packages, a rotary goods 5 ejector plate 25 below and free of said cabinet and having a rectangular opening 34 corresponding with and directly below the open lower end of said chamber and being of a depth to receive the lower one of said packages and of an outline to engage the edges of said package for turning it individually on its central vertical axis, and a base-plate 22 below said rotary goods ejector plate having a rectangular opening 39 cor- 10 responding with and directly below the open bottom of said chamber and said opening 34 and standing in cross-angular relation to the open bottom of said cabinet so that said base-plate may support the stack of pack- 15 ages at the four corner portions of the same over said opening 39 in the inoperated position of said goods ejector plate and said goods ejector plate support said stack at its four corner portions when in its operated 20 position, said ejector-plate having means for operating it, combined with a receptacle 42 below the said plate 22 to receive the packages which fall through said opening 39, said receptacle being provided with an opening 43 for the removal of the packages there- 25 from; substantially as set forth.

2. In a vending machine, a cabinet containing a vertical chamber which is rectangular in cross-section and adapted to snugly receive a stack of uniformly piled rectangular packages to be sold, the bottom of said chamber being entirely open, as at 26, for the descent of said packages, a rotary goods ejector plate 25 below and free of said cabi- 30

net and having a rectangular opening 34 40 corresponding with and directly below the open lower end of said chamber, and being of a depth to receive the lower one of said packages and of an outline to engage the edges of said package for turning it in- 45 dividually on its central vertical axis, and a base-plate 22 below said rotary goods ejector plate having a rectangular opening 39 cor- 50 responding with and directly below the open bottom of said chamber and said opening 34 and standing in cross-angular relation to the open bottom of said cabinet so that said base-plate may support the stack of pack- 55 ages at the four corner portions of the same over said opening 39 in the inoperated position of said goods ejector plate and said goods ejector plate support said stack at its four corner portions when in its operated position, and a frame at the lower end of the cabinet comprising a plate 19 having an up- 60 wardly extending flange 20 to receive the lower edges of the cabinet and downwardly extending flanges 21, 23 engaging the said base-plate and affording a chamber for said goods-ejector plate, said ejector-plate having means for operating it, combined with a re- 65 ceptacle 42 below the said plate 22 to receive the packages which fall through said opening 39, said receptacle being provided with an opening 43 for the removal of the pack- 70 ages therefrom; substantially as set forth.

Signed at New York city, in the county of New York, and State of New York, this third day of August A. D. 1908.
